John A. Gaylord, Pacific Palisades, Calif.

Application December 28, 1953, Serial No. 400,516

8 Claims. (Cl. 244—150)

This invention relates to a device for automatically releasing a parachute.

The parachute release of the present invention is designed to operate with as little effort as possible on the part of the operator. The release of the present invention comprises an assembly of three units, each unit being constructed so that it can be built separately and tested separately before the three units are assembled or joined together, and in this way the construction is simplified, the testing operation is simplified, and the device insured against failure, and results positive in operation.

The first unit of the present invention consists of an air pressure bottle which contains air pressure sufficient for actuation of the parachute rip cord. The release of the present invention in its preferred form has been designed to have a pressure of about 200 pounds pull on the rip cord, which is about five times the pressure required for operating the same. The first unit of the invention includes, in addition to the air bottle, a needle for piercing the air bottle. This needle is mounted on a piston normally urged to piercing position by a spring and there is provided a release pin for this piston normally restraining its operation. The initiation of the actuation of the device of the present invention is by pulling this release pin so that the needle may pierce the air bottle whereupon the released air pressure will operate upon the piston mounting the piercing needle so as to retract the same into position where it is again held by the release pin. The first unit of the present invention also includes a cocking bar for utilization in cocking the spring-actuated piston holding the piercing needle. This unit is constructed so as to be mainly mounted in a tube and adapted to be tested independent of the remaining units of the invention, the remaining units being connected thereto by an air tube.

The second and main unit of the present invention is a valve and actuating mechanism designed to regulate the passage of the actuating air pressure from the first unit to the third unit or rip cord actuating unit. The valve and valve-actuating mechanism comprises a valve which is connected for operation to a vacuum bellows provided with suitable adjusting means, the vacuum bellows being intended for normally actuating a valve in the pressure supply system only after a fall to a particular altitude corresponding to that for which the vacuum bellows is adjusted to function. The valve and actuating means of this second unit also includes valve means adjustable for regulating the rate of flow of air pressure to the rip cord pulling unit after the vacuum bellows has opened the valve associated therewith. This unit is likewise assembled in the tube complete for operation and testing independent of the other elements.

The third and separately constructed unit of the present invention is the rip cord pulling element which comprises an air-actuated piston to be connected with the rip cord of the parachute. This air piston is designed to provide about a four inch pull on the rip cord, and the

2

unit has also associated therewith an exhaust valve and an adjustment valve for regulating the rate of exhaust after the exhaust valve has been opened. This unit may be completely constructed and assembled and tested as a separate unit independent of the other elements of the parachute release of the present invention.

The parachute release of the present invention requires very little effort on the part of the operator. He is merely required to pull the release pin which holds the piston carrying the bottle-piercing needle. Thereafter the actuation of the parachute release is automatic. If the operator is going to jump at a higher altitude than the device is set for operation, the release pin may be pulled by the operator before he jumps and the operator will descend without the parachute opening until the altitude is reached at which the release is set for operation. When this altitude is reached a slow but positive pull is applied to the rip cord of the parachute to open the same, and adjustment means are provided so that the operation of pulling and opening the chute may take place any desired time after the proper altitude is reached, such for example, as four seconds.

The parachute release of the present invention may also be used when the operator is required to jump at a lower altitude than the one for which the release is adjusted for operation. In such a case the release of the present invention will start to operate immediately after the release pin for the bottle-piercing needle has been pulled but there will be a regulated period of time, such for example, as four seconds, before the operation of pulling the rip cord has been completed.

The aneroid barometric parachute release of the present invention, together with further advantages of the invention, will be fully understood from the following description of the preferred example of the invention. For that purpose I have hereafter described a preferred example of the invention in connection with the accompanying drawings, in which:

Figure 1 is a side elevation mainly in vertical section; 40 Figure 2 is an end elevation; and

Figure 3 is a fragmentary plan view of certain of the adjusting means employed for setting the altitude of operation of the vacuum bellows.

Referring to the drawings, 1 indicates an outer casing 45 or body in which the three main and separately constructed and tested units of the present invention are mounted. The first unit of the present invention comprises a tube 2 which serves mainly as a container for the air bottle 3. A screw cap 4 is provided at the end 50 of the tube 2 by means of which the air bottle has its neck pressed against a flexible seat 5. As pointed out, the air bottle 3 is closed at its neck by a wall adapted to be pierced by a needle 6, and the air bottle normally will contain air pressure, such for example, as 1000 pounds. 55 The piercing needle is mounted by a needle retainer 6a in turn threaded to a piston 10. The piston 10 is movable in a cylinder 18, which is threaded to the bottle containing tube 2 and provides a mounting for the flexible bottle seat 5.

60 The piston 10 is provided with a flexible airtight cup 8 normally pressed against the bore of the cylinder 18 by ring expansion spring 9. At the end of the cylinder 18 there is provided a cap 16 and a piston spring 11 is mounted between this cap and the shoulder of the piston 65 for normally urging the piston in the direction to cause the needle 6 to pierce the air bottle 3. The space in the cylinder 18 back to the rear of the flexible cup 8 is vented to the atmosphere by air holes 17a. The piston 10 is provided with an annular groove which receives a pin forming part of a combined piston and release pin 20, and the cylinder 18 has a laterally extending tubular portion mounting this piston ring release spring

at the end of which there is provided a cap 22 having a central aperture through which extends a pull cable 23 which is attached to the piston and release pin 20. A spring 21 normally urges the release pin towards the piston 18 under a mild pressure, such for example, as about 4½ pounds.

The first unit also includes a cocking bar 12 which is threaded to the cap 16, and preferably externally of the cap, with the knob 13. The cocking bar 12 enters a bore of the piston 10 and at its inner end is provided with a ring 15 pinned to the cocking bar, which ring 15 is intended for contacting a retaining ring 14 affixed to the cylinder 18. The cocking bar is for moving the piston 10 to the position indicated in Figure 1 or the cocked position. For this purpose the cocking bar is unscrewed from the cap 16 and pulled to the left until the pin 20 drops in the groove of the cylinder 10. It is normally only necessary to use the cocking bar once in the use of the release of the present invention since after each operation the piston is automatically returned to the cocked position.

When the piston 10 is in the retracted position, as indicated in the drawing, there is an air space 7 between the flexible cup 8 and the bottle 3 and an air outlet 24 is provided by which the first unit is connected by an air tube 24a with the second unit.

The second unit comprises a valve body 25 which also serves to mount a porous air filtering medium 26 in a recess closed by a filter cap and gasket 26a. The air entering the tube 24a passes through the filtering medium 26 to an air passage 27 which, as viewed in Figure 1, is indicated as closed by a needle valve 28. The needle valve 28 is mounted by a valve shaft 29 which is enlarged, as indicated at 29a, to provide a second valve seat for sealing an exhaust outlet. This valve head 29a is movable as later explained, into contact with the flexible valve seat 30 thereby closing off the exhaust of air around the valve shaft 29. Beyond the needle valve 28 there are air ports, one branch of which leads to the apparatus shown in the position of Figure 1, to the exhaust passage around the valve shaft. The other branch leads to an air regulating valve 32 which is a screw threaded valve engaging a packing nut 32a, in turn engaging the packing 32b. This valve regulates the flow of air to the rip-cord pulling element of the invention so as to provide a desired time delay interval, as hereafter more fully explained.

The valve body 25 is threaded to the cap 33 which also provides a supporting means for the flexible valve seat 30. The valve shaft 29 is threaded to the case 36 of a vacuum bellows and a locknut 35 is provided.

The vacuum bellows of the present invention has within its case 36 a plurality of collapsible bellows members 43 mounted spaced apart by spacers 42. The vacuum bellows of the present invention is one in which the space 41 in the case exterior to the bellows 43 is intended to be evacuated, for which purpose the evacuated tip 41a is indicated. The bellows members are intended to interiorly have a pressure equal to atmospheric pressure, and accordingly the greater the atmospheric pressure the greater will be the relative expansion and spacing between independent bellows members 43. A bellows shaft 37 is provided which is enlarged at its right end to contact the righthand bellows 43. This shaft is in turn attached to an adjustment screw 38. The adjustment screw 38 is provided with two adjusting nuts 46 by means of which its axial position may be varied. The adjusting nuts 46 contact on one side the block 47 affixed to a mounting tube 49 and at the other end block 48 are affixed to the tube 49 and held in spaced relation by the pin 39. The tube 49 extends to the end of this unit and supports the valve body 25 in rigid spaced relation with the block 47 and block members 48. There is also provided an adjusting nut 44 threaded to the adjustment screw 38, which nut 44 provides a seat for the spring 40 which engages the case 36 of the vacuum bellows. This

nut 44 thereby provides a means for adjusting the spring pressure urging the bellows case to the right, as viewed in Figure 1, in the direction of closing the valve needle 28. The nut 44, as shown in Figure 3, is preferably knurled and graduated, the graduation indicating the altitude at which the needle valve 28 will be retracted from its seat.

The tube 49 is preferably provided with a sliding door 49a which normally covers the adjusting nut 44 but which may be opened when it is desired to set the proper altitude of operation of the device. There is also provided a cover plate and indicator 80 which is provided with a wire cooperating with the graduation on the adjusting nut 44. This plate 80 is removed from the tube 49 when (at the factory) the adjusting nut 46 is to be set. There is preferably provided on the block 47 a spring-pressed dog 45 which is to engage cooperating recesses in the pressure adjusting nut 44 for yieldingly locking said nut in an adjusted position.

The second unit with all its elements assembled with or mounted by the tubing 49 may be completely tested independently of the other units and is assembled in the completed release of the present invention merely by connection with the case 1, the use of tube 24a, and also a tube 34 connecting the discharge of the air passage 31 in to the pneumatic release plunger unit, which is the third unit of the device of the present invention. This unit comprises the pneumatic piston 50 which is provided with a flexible cup leather 51 behind which is a ring expansion spring 52 which forms a pneumatic seal with the walls of a tube 75 which forms the cylinder of the pneumatic plunger. A retaining nut 53 is provided for retaining the flexible cup leather 51 to the piston 50 and this nut also has affixed thereto the parachute release wire 60 which is to be pulled for opening the parachute. The wire 60 is attached to the nut 53 by a nut 54 preferably held in position by a lock screw 55. The cylinder 75 is indicated as having a head providing a packing seat and screw 62 for supporting a graphite packing 61 contacted by a wire housing retainer 63. Within this wire housing retainer 63 extends a wire housing tube 64 which consists essentially of a parachute release wire 60 around which is a spirally wound square wire 56 and a woven insulating cover.

There is also provided a collar 65 on the piston 50 which contacts a valve 66 retaining that valve closed against the flexible seat 68 until the piston 50 has traveled to the left sufficiently to release valve 66. Opposite the valve 66 on the cylinder 75 there is provided a bearing block 67 which contacts collar 65. A valve retaining nut 69 is provided for retaining the flexible valve seat 68 in position and this nut contacts gasket 70. Here the channel 71 leads from the nut 69 to an adjusting valve 74 which may be employed for adjusting the rate of flow through passage 71. The adjusting valve 74 includes a packing nut 74a engaging the packing 74b. From the valve 74 air may be exhausted to the atmosphere. The cylinder 75 is closed at its left end with a cap 78 provided with an air hole 77 and an escape air hole 76 is provided in the cylinder 75 close to the cap 78. This third unit of the present invention is likewise adapted for complete assembly and testing independently of the other units.

In use of the aneroid barometric parachute release of the present invention when the first unit is originally constructed and assembled the piercing needle 6 is moved to the cocked position by utilization of the cocking bar 12. The air bottle 3 is then inserted and held in place by the cap 4. Whenever the pull cord 23 is pulled the piercing needle 6 will pierce the air bottle 3 whereupon the air pressure from that bottle will enter space 7. The piercing needle which is mounted by the cylinder 10 will be promptly forced back by the air pressure to the cocking position where it will be automatically held by the spring-actuated release pin 20. Air pressure from the bottle 3 passes from the space 7 through tube 24a to the second

unit where it encounters the needle valve 28 and here is restrained from further movement until needle 28 is actuated. The air passage beyond needle valve 28 is at this time connected with an exhaust opening to the atmosphere whereby there is eliminated any vacuum or air pressure locked in the system. As the parachute drops the atmospheric pressure with the bellows members 43 increases with the resulting pressure tending to increase the space between successive bellows members or to urge the bellows case 36 to the left against the action of the spring 40. This action is resisted by spring 49 until the altitude is reached at which the device was set to operate, whereupon the case 36 moves to the left taking valve 28 from its seat. Simultaneously, the valve 29a closes the exhaust port by contacting the flexible seat 30. The air from the bottle 3 now passes to the valve 32 which has been set into a position to allow a regulated rate of flow of air to tube 34 against the pneumatic plunger or piston 50 which is to actuate the parachute release wire. The pressure builds up against the pneumatic piston regulated by the valve 32 causing a pull on the rip cord with a movement of the piston or plunger to the left until eventually collar 65 clears the valve 66 in which an exhaust port of that line 71 is opened to the atmosphere. This exhaust is also regulated by a valve.

After one use of the parachute release of the present invention it is simply necessary to insert a new air bottle 3 in place of the exhausted unit and reconnect the nut 53 to the release wire to be actuated by the unit.

While the particular form of the invention herein illustrated is well designed to carry out the objects of the present invention, this invention is of the scope set forth in the appended claims.

I claim:

1. A parachute release comprising, an air bottle, mechanism for piercing said air bottle, an air passage for air from the pierced bottle to a pneumatic piston, means for attaching a parachute release wire to said piston, valve means in said passage, a vacuum bellows for opening said valve at a predetermined atmospheric pressure, said vacuum bellows including a casing having a plurality of bellows members mounted therein, a shaft attached to said bellows members, adjusting means for mounting said shaft, an adjusting nut on said shaft, and a spring between said nut and the case of said vacuum bellows.

2. A parachute release comprising, an air bottle, mechanism for piercing said air bottle, an air passage for air from the pierced bottle to a pneumatic piston, means for attaching a parachute release wire to said piston, valve means in said passage, a vacuum bellows for opening said valve at a predetermined atmospheric pressure, an adjusting valve independent of said bellows actuated valve for regulating the rate of flow of air to said parachute release wire actuating piston, and an exhaust line from said piston, including a further valve means for adjusting the rate of discharge from said exhaust.

3. A parachute release comprising, an air bottle, mechanism for piercing said air bottle, an air passage for air from the pierced bottle to a pneumatic piston, means for attaching a parachute release wire to said piston, valve means in said passage, a vacuum bellows for opening said valve at a predetermined atmospheric pressure, an exhaust passage connected to the air passage between said valve and piston, and valve means for closing said exhaust actuated on the operation of said vacuum bellows.

4. A parachute release comprising, essentially three units, each adapted to be separately constructed and tested, and means for supporting the three units with air tube connections between the same, one of said units com-

prising an air bottle, an air bottle piercing mechanism, and a release pin for said piercing mechanism, the second unit comprising a vacuum bellows actuating valve mechanism for controlling the rate of flow from the air bottle to the third unit, said mechanism including means for adjusting said mechanism to operate at a desired atmospheric pressure, and the third unit comprising a pneumatic piston for attachment to a parachute release wire actuated by air pressure under the control of the mechanism of the second unit.

5. A parachute release comprising, essentially three units, each adapted to be separately constructed and tested, and means for supporting the three units with air tube connections between the same, one of said units comprising an air bottle, an air bottle piercing mechanism, and a release pin for said piercing mechanism, the second unit comprising a vacuum bellows actuating valve mechanism for controlling the rate of flow from the air bottle to the third unit, said mechanism including means for adjusting said mechanism to operate at a desired atmospheric pressure, and an exhaust line for the passage between said valve and piston, and means actuated by said bellows for closing said exhaust valve.

6. A parachute release comprising, essentially three units, each adapted to be separately constructed and tested, and means for supporting the three units with air tube connections between the same, one of said units comprising an air bottle, an air bottle piercing mechanism, and a release pin for said piercing mechanism, the second unit comprising a vacuum bellows actuating valve mechanism for controlling the rate of flow from the air bottle to the third unit, said mechanism including means for adjusting said mechanism to operate at a desired atmospheric pressure, and the third unit comprising a pneumatic piston for attachment to a parachute release wire actuated by air pressure under the control of the mechanism of the second unit, and an exhaust line for said piston, a valve actuated by said piston.

7. A parachute release comprising a pneumatic piston having means for attachment to a parachute release wire, a bottle for retaining air under pressure normally sealed, a passage from said bottle to said pneumatic piston, a second piston having a piercing element movable to pierce the seal of said air bottle and movable on piercing of said seal to retracted position, spring means for normally urging said latter piston to the piercing position, and a spring-pressed release pin normally maintaining said latter piston in retracted position.

8. A parachute release comprising, a pneumatic piston having means for attachment to a parachute release wire, a bottle for retaining air under pressure normally sealed, a passage from said bottle to said pneumatic piston, a second piston having a piercing element movable to pierce the seal of said air bottle and movable on piercing of said seal to retracted position, spring means for normally urging said latter piston to the piercing position, a spring-pressed release pin normally maintaining said latter piston in retracted position, a barometric actuated valve in the line between said air bottle and a parachute wire actuated piston, and means for adjusting said barometric actuated valve to operate at a predetermined altitude.
